Primary Examiner — Karen S Acker*(74) Attorney, Agent, or Firm* — Laura L. Bozek(57) **CLAIM**

The ornamental design for a paper sheet product, as shown and described.

DESCRIPTION

FIG. 1 is a top view of a first embodiment of a paper sheet product in a position of use within a paper roll drawn in broken lines and gray scale illustrated in perspective; and, FIG. 2 is a top plan view of a second embodiment of a paper sheet product.

The inner broken line surrounding the paper sheet product depicts the boundary of the claim and forms no part thereof. The broken lines, greyscale features and areas outside of the boundary depict environmental subject matter that forms no part of the claimed design.
